WILLIAM CURRY STEPHENSON, OF ROCKY MOUNT, NORTH CAROLINA.

LOCOMOTIVE-AXLE BEARING.

1,079,809.

Specification of Letters Patent. Patented Nov. 25, 1913.

Application filed November 11, 1912. Serial No. 730,637.

To all whom it may concern:

Be it known that I, WILLIAM C. STEPHENSON, a citizen of the United States, and a resident of Rocky Mount, in the county of Edgecombe and State of North Carolina, have invented an Improvement in Locomotive-Axle Bearings, of which the following is a specification.

The journal blocks or bearings of locomotive axles are commonly inserted from below in slots provided in the frame and are secured by wedges commonly termed "wedge-bolts". When the latter break, or for other reason require to be removed and replaced, it is necessary to first remove the horizontal bar, or so-called "binder", by which the wedge-bolt is supported.

This operation involves considerable time and labor and it is the object of my invention to provide an improvement whereby the removal of the wedge-bolt can be very easily and quickly effected.

The details of construction, arrangement, and combination of parts are as hereinafter described, and illustrated in the accompanying drawing, in which—

Figure 1 is a vertical section of a portion of a locomotive frame, together with journal bearings and my improved attachment applied thereto. Fig. 2 is an enlarged vertical section illustrating particularly the means for supporting and adjusting the wedge. Fig. 3 is an enlarged longitudinal section of the screw collar in which the bolt for adjusting the wedge is arranged. Fig. 4 is a plan view, and Fig. 5 is a longitudinal section of the so-called binder. Fig. 6 is a perspective view of the screw collar of the adjusting wedge-bolt. Fig. 7 is a sectional view further illustrating the construction and arrangement of wedges for securing the brace or binder to the locomotive frames.

Referring in the first instance to Fig. 1, the numeral 1 indicates an axle-journal, 2 the block or bearing for the same, and 3 the locomotive frame in whose vertical slot the block 1 is arranged. 4 indicates the wedge which is inserted in a cavity or recess on one side of the journal-block 2 and whose outer or inclined side is in sliding contact with the correspondingly inclined side of the adjacent frame. The wedge 4 is supported upon, and adjusted by, a screw-bolt 5 having a conical head which is in contact with the wedge and adapted for lateral insertion in opposite grooves 6, which are

preferably dove-tailed so that the shoulders of the bolt head engage the wedge.

The wedge-bolt 5 passes through a so-called collar 7, shown detached in Figs. 3 and 6. The body of this collar is cylindrical and screw-threaded internally and externally, and the head, which is narrow in one direction, extends horizontally, thus forming ears which, when the collar is arranged in a slot 8 provided in the binder or horizontal bar 9, extend across and rest upon the binder, as in Figs. 1 and 2. The wedge-bolt 5 is screw-threaded and thus adapted to engage the thread formed in the upper portion of the collar 7, and a nut 10 is applied to the lower end of the collar, as shown. A jam-nut 11 is also applied to the lower end of the bolt and locks the nut 10 so that it is immovable.

The ears 7^a of the collar rest in notches 9^a formed in the top of the binder 9, so that the collar cannot rotate when the parts are in the position shown in Fig. 1, and the nut 10 is being screwed home to hold the collar 80 in place. The lower end of the wedge-bolt 5 is squared to provide for the application of a wrench for turning it, for the purpose of adjusting the wedge 4 higher or lower. The slot 8 in the binder 9 is long enough to 85 permit the lateral adjustment of the collar 7 and wedge-bolt 5 held therein, so that these parts may be placed in the position shown by full lines in Fig. 1.

In order to place the parts in position, the bolt 5 is screwed into the collar 7 and the latter then inserted up through the slot 8 and the ears or extended head of the collar are turned crosswise of the binder, as shown by dotted lines in Fig. 4. The wedge-bolt 5 and collar 7 are then adjusted laterally into the position shown by full lines in Fig. 1, the conical head of the bolt 5 entering the groove 6 in the wedge and the ears 7^a of the collar dropping into the notches 9^a of the binder. Then the nut 10 is turned to draw the collar 7 tightly into place, and the wedge-bolt 5 is rotated to adjust the wedge tightly as required. The jam-nut 11 is next rotated to lock the nut 10 and the operation 105 is repeated.

In order to disengage the wedge-bolt 5 from wedge 4, the adjusting bolt 5 is loosened and also the collar 7, so that they may be slid together laterally to the right, and into the position indicated by dotted lines in Fig. 1. The binder or brace 9 is provided

with vertical slots 9^a to receive downwardly projecting lugs 12 of the locomotive frame 3, and also with transverse or horizontal slots 9^b to receive the wedges 13, whose outer sides are inclined, as shown in Fig. 7, and work in contact with the correspondingly inclined outer sides of the slots 9^b. The two slots open into each other, as will be readily understood from the drawing. Nuts 14 are applied to the reduced, threaded cylindrical ends of the wedges 13, and serve as means for adjusting the latter lengthwise, whereby they may be forced against the frame lugs 12, so as to clamp the binder 15 tightly thereto.

What I claim is:—

1. The combination with a locomotive frame, an axle-journal bearing, a wedge, and a horizontal bar beneath the bearing 20 and wedge, of a bolt extending through an opening in said bar, a collar surrounding and adapted to retain said bolt within the opening, means on the upper end of said collar engaging said bar.
2. The combination with a locomotive frame, an axle-journal bearing, a wedge, and a horizontal bar beneath the bearing and wedge, of a bolt extending through an opening in said bar, a collar surrounding 30 said bolt provided with an interior threaded portion, a holding means on end of said collar, and means on the body of the collar engaging said bolt to retain the device when said holding means is in operation.
3. The combination with a locomotive frame, an axle-journal bearing, a wedge, and a binder beneath the bearing and wedge, of a bolt extending through an opening in 35 said binder, a collar surrounding said bolt 40 provided with an interior threaded portion, a nut on its lower end engaging a recess in the bottom surface of the binder, and oppositely disposed laterally extending lugs and its upper end adapted to engage a recess in

the top surface of the binder to hold the 45 device in operative position when the nut is tight.

4. The combination, with a locomotive frame, an axle-journal block arranged therein, and a wedge inserted between the block 50 and frame, of a horizontal bar attached to the frame and extending beneath the block, said bar being provided with a lengthwise slot adapted for lateral adjustment of means for adjusting the wedge, said means consisting of a screw-bolt, and an internally threaded collar through which it is inserted, said collar being provided with means for supporting it in the slot of the bar, as described.

5. The combination, with a slotted locomotive frame, a journal-block arranged in the slot, and a wedge arranged between them, as described, of a horizontal bar arranged below the journal-block and secured to the frame and provided with a lengthwise 65 slot at a point directly below the wedge, and a device for adjusting the bolt vertically, the same consisting of a screw-bolt and a screw-threaded collar through which it passes, said bolt and collar being adapted 70 for support in the slot of the bar and for adjustment laterally to one side of the wedge, as set forth.

6. The combination, with a frame, an axle-bearing block and wedge coacting therewith, 75 of a horizontal bar secured below the bearing and provided with a longitudinal slot and notches formed in the upper side, a screw bolt and a screw-collar through which it passes, said collar being arranged in the 80 slot of the bar and provided with lateral extensions adapted to fit in the aforesaid notches of the bar, as described.

WILLIAM CURRY STEPHENSON.
